UNITED STATES PATENT OFFICE.

LEWIS HALLOCK NASH, OF SOUTH NORWALK, CONNECTICUT, ASSIGNOR TO
THE NATIONAL METER COMPANY, OF NEW YORK, N. Y.

DESIGN FOR A FRAME FOR GAS-ENGINES.

SPECIFICATION forming part of Design No. 30,030, dated January 17, 1899.

Application filed January 25, 1897. Serial No. 620,692. Term of patent 14 years.

To all whom it may concern:

Be it known that I, LEWIS HALLOCK NASH, a citizen of the United States, and a resident of South Norwalk, in the county of Fairfield and State of Connecticut, have invented a certain new and original Design for a Frame for Gas-Engines, of which the following is a specification.

My design is exhibited in the accompanying drawings, which show, in—

Figure 1, a frame for a gas-engine in front view; and Fig. 2 shows the same frame in side elevation.

Referring to the drawings, 2 2 are upright cylinders set side by side and each having a projecting panel forming part 7 at its upper front end, united by a tubular part 8 8, crossing them. At their lower ends the cylinders are reduced in diameter and terminate in a rectangular base-flange. Below these cylinders is a subbase 3, of rectangular form, which

joins by a flange 20 the flange of the cylinders. This subbase tapers to the top flange and has a rectangular base-flange 21. A pillar-bed 4, of rectangular form, joins the subbase by a flange, which forms a seat and a support for it. The longest side walls of this base curve from its top flange outward to its base and give to the subbase an approximately pyramid form.

On the line of the joining flanges of the two base structures a cylindrical opening 5 is formed, running through from end to end, the whole forming a twin upright frame for a gas-engine.

What I claim is—

The design for a frame for gas-engines substantially as described.

LEWIS HALLOCK NASH.
